DESIGN FOR A CHAIR

William J. Bargen, Waukegan, Ill.

Application July 27, 1942, Serial No. 107,718

Term of patent 14 years

To all whom it may concern:

Be it known that I, William J. Bargen, a citizen of the United States of America, residing at Waukegan, in the county of Lake and State of Illinois, have invented a new, original, and ornamental Design for a Chair, of which the following is a specification, reference being had to the accompanying drawing, forming a part thereof.

In the drawing:

I claim:

The ornamental design for a chair, as shown.

WILLIAM J. BARGEN.
